BELL TOWER

Kenneth H. Ripnen, Rye, N.Y.

Application July 3, 1957, Serial No. 46,824

Term of patent 14 years

(Cl. D13—1)

Fig. 1.

Fig. 2.

Fig. 3.

Fig. 4.

Fig. 5.

Fig. 1 is a front elevation of a bell tower embodying my new design;

Fig. 2 is a back elevation view thereof;

Fig. 3 is a side elevation thereof;

Fig. 4 is a top elevation thereof;

Fig. 5 is a cross-sectional view thereof taken through line 5-5 of Fig. 3.

For convenience of illustration only parts of the stone surface have been shaded in Figs. 1, 2 and 3. It is to be

understood that the stone surface continues throughout the plain areas shown.

I claim:

The ornamental design for a bell tower, substantially as shown and described.
